UNITED STATES PATENT OFFICE.

GEORGE LEE BENDER, OF SAN FRANCISCO, CALIFORNIA.

BOTTLE-LABELING MACHINE.

1,072,403.

Specification of Letters Patent. Patented Sept. 2, 1913.

Application filed July 3, 1912. Serial No. 707,438.

To all whom it may concern:

Be it known that I, GEORGE LEE BENDER, a citizen of the United States, residing in the city and county of San Francisco and State of California, have invented certain new and useful Improvements in Bottle-Labeling Machines, of which the following is a specification.

The hereinafter described invention relates to an improved apparatus for applying labels to filled bottles or other containers, and the same comprises a reciprocating conveyer provided with suitable carriers for sustaining the bottles placed thereon, endless conveyer chains for placing the labels within the path of the propelled bottles, label pickers carried by said endless conveyer chains, devices for applying an adhesive to the face of said label pickers, a label container and means within the same for removing a label therefrom and positioning the same adjacent the adhesively coated label picker, means for forcing the label against the adhesively coated label pickers, the said pickers adapted to position the label in the path of the propelled bottle, devices for wiping the labels onto the propelled bottles, means for holding the labels to the surface of the propelled bottles while the same are being wiped thereon, and conveyers for removing the labeled bottles from the labeling machine. The construction of the co-acting working parts is such that the label pickers carried by the endless conveyer chains for placing the label in the path of the propelled bottle, are not supplied with adhesive or a label unless a bottle is positioned in the carrier and conveyed toward the labeling mechanism, hence in the operation of the apparatus if a bottle is not conveyed toward the labeling mechanism, the mechanism for coating the label pickers with adhesive or forcing the label against the adhesively coated label pickers is not thrown into operation, consequently—no bottle, no label feed.

The object of the invention is to render automatically the work of applying labels to filled bottles, to provide against the feeding of labels in case no bottle is presented for labeling, thereby providing against the waste of material and delay in the operation of the apparatus, to materially expedite the work of labeling the bottles, and by doing so materially increasing the output of the label-

ing plant and correspondingly reducing the cost of labeling the bottles.

With the above mentioned and other objects in view, the invention consists in the construction and novel combination of parts hereinafter fully described, illustrated in the accompanying sheets of drawings, forming a part of this invention, and pointed out in the claims hereto appended; it being understood that various changes in the form, proportion, size and minor details of construction within the scope of the claims hereto appended, may be resorted to without departing from the spirit or sacrificing any of the advantages of the invention.

To comprehend the invention, reference should be had to the accompanying sheets of drawings illustrating a complete constructed apparatus for successively carrying out the invention, wherein—

Figure 1 is a side elevation of the machine with a portion of the frame partly broken away, disclosing the reciprocating conveyer for the bottles to be labeled and the mechanism for operating the same, the adhesive applying means, the label boxes and the means for removing a label from the boxes and placing it in the path of the endless conveyer chains. Fig. 2 is a plan view of the machine looking downward from line 2—2 Fig. 1, with the bed plate partly broken away, disclosing one of the supporting tracks for the reciprocating conveyer, the pivoted arms actuated by the bottles to be labeled for operating the no bottle no label feed device, the flexible wipers for applying the labels to the bottles, the arms for holding the label onto the face of the bottle while it is being wiped thereon, and the conveyers for removing the labeled bottles from the labeling machine. Fig. 3 is an elevation of the discharge end of the machine, taken on line 3—3—Fig. 2, disclosing the reciprocating conveyer for the bottles to be labeled, the neck and body label boxes, the adhesive containing receptacles and the adhesive applying rolls therein, the endless conveyer chains carrying the label pickers, the means for applying an adhesive to the label pickers, the operating means for removing a label from the label boxes and positioning it on the label pickers, the flexible wipers for wiping the adhesively coated label onto the bottle, and the endless conveyer belts for removing the labeled bottles from the ma-

chine. Fig. 4 is an enlarged broken detail plan view of the fingers for holding the label to the surface of the bottle, the flexible wipers, the label pickers carrying a label, the same being positioned to be applied to the surface of the advancing bottle. Fig. 5 is an enlarged side elevation taken on line 5—5, Fig. 4, with the label feeding device and label picker chains left out, disclosing the support on which the arms slide, the mechanism for holding the arms in an alined position as the label is being applied to the bottle, the devices for engaging said arm alining means, the mechanism for removing the arms from the labeled bottle, and the means for returning the arms to an alined position for engagement with the next label to be applied. Fig. 6 is an enlarged broken detail, in elevation, looking from the discharge end of the machine, disclosing the neck and body label boxes, and the supporting frame therefor partly broken away, disclosing the mechanism for positioning the label onto the adhesively coated label pickers. Fig. 7 is an enlarged broken detail side elevation of Fig. 6, looking in the direction of the arrow—Fig. 6, disclosing the label pickers carried by the endless chains, the mechanism for removing the labels from the boxes, and the devices for positioning the labels onto the adhesively coated label pickers. Fig. 8 is an enlarged diagrammatic top plan of the bottle, label holding fingers, and wipers, disclosing the wipers in their operation of wiping a label onto the bottle, and in dotted lines showing the position of the wipers immediately after wiping the label in place, the direction of the travel of the bottle being indicated by the arrow. Fig. 9 is an enlarged diagrammatic top plan of the bottle, and wipers showing the wipers just springing back into normal (dotted) position as the bottle travels forward to the delivery belt, the direction of travel being shown by the arrow. Fig. 10 is an enlarged diagrammatic top plan view of the compass legs that carry the label holding fingers, showing the same as in position in Fig. 4, also showing the stop lugs that force the compass legs into an alined position, the dotted lines disclosing the upper leg, and the lug disclosed in section being carried thereby. Fig. 11 is a view similar to Fig. 10, disclosing the compass legs in a closed position, as in dotted lines—Fig. 4. Fig. 12 is an enlarged detail side elevation of the adhesive receptacle, disclosing the adhesive feed and applying rolls and the direction of travel of the same. Fig. 13 is a top plan view of the adhesive receptacle as disclosed in Fig. 12.

The machine disclosed in the drawings is capable of labeling two bottles at one operation, but it is to be understood that this is merely for illustration, as it is intended

that the machine may be constructed as a single or multiple bottle labeling machine.

In the detailed description of the machine, the terms "inner or front" of the machine refer to that part adjacent or facing the bottle feed end of the machine, and the terms "outer or rear" refer to that part adjacent or facing the bottle delivery end of the machine.

In the drawings, referring more particularly to Figs. 1 and 3 thereof, the reference numeral 1 designates a suitable supporting frame adapted to carry the bottle feed and drive mechanisms, and is provided at one end with a pair of oppositely spaced vertically extending upright portions or arms 1', which are adapted to carry the label affixing and applying mechanisms. Mounted in journals near the rear of the frame 1 and below the arms 1' is a drive shaft 2, adapted to receive power from any suitable source, and to transmit the same by a suitable drive belt 3, to a driven shaft 4 journaled in the frame near the front end thereof. The driven shaft 4 is provided intermediate the inner side walls of the frame 1 with a pair of curved cam arms 5 which when rotated with the driven shaft in the direction of the arrow (Fig. 1), engage the forward face of a conveyer plate 6, to the upper edge of which is attached the forwardly curved uprights 7, which project through suitable slots 8 in the top 9 of the frame, and to the ends of which are attached the lower edges of semi cylindrical bottle carriers 10; the cams 5 moving the plates and the parts carried thereby toward the labeling mechanism of the machine. The plate 6 is provided at the top and bottom of each of the side edges thereof with oppositely extending alined arms 10', to the outer ends of which are rotatably mounted suitable grooved wheels 11 which engage beads or tracks 12, secured to the inner faces of the sides of the frame, the tracks providing a guide-way for supporting the conveyer plate 6. The conveyer plate 6 is returned to its normal position after the cam arms 5 have passed the lower edge thereof in their cycle of movement, by a pair of suitable weights 13, each attached to one end of a flexible connection 14, extending over the pulleys 15 mounted on the forward end of the frame 1, and the opposite ends thereof being attached to the plate, as at 16. The inner ends of the slots 8 are provided with yieldable rubber bumpers 8' which relieve the jar caused by the return movement of the conveyer plate 6.

The bottles to be labeled are placed in the bottle carriers 10 and advanced along the top 9 of the frame through the label applying mechanism, disclosed more fully in Figs. 2, 3, 4 and 5 of the drawings, and which is operated in the following manner:—Loosely mounted on one end of the

drive shaft 2, between the side of the frame 1 and the drive belt 3 is a toothed sprocket wheel 17, the hub portion of which is provided with an inwardly extending bevel face 17', which is adapted to be frictionally engaged by the cone face 18' of a clutch 18 keyed to rotate with the drive shaft 2. A suitable linked drive chain 19 extends around the wheel 17 and a suitable gear wheel 20 keyed to the end of a shaft 21 which is journaled in bearings at the extreme upper ends of the upright arms 1', the shaft 21 mounting suitable toothed gear wheels 22, which are arranged in pairs between the uprights 1' and support the upper ends of endless label picker chains 23, the lower ends of the chains extending around suitable toothed idlers 24 and 25 journaled at the ends of suitable plates 26, one of said plates being secured to the top frame plate 9 at each side of the slots 8, and directly below the shaft 21, as disclosed in Figs. 2, 3 and 4 of the drawings. The label picker chains 23 are provided with suitable inwardly projecting lugs or fingers 27, arranged in pairs on the respective chains and positioned opposite each other on each pair of chains, as in Fig. 3 of the drawings, the lugs having attached to the outer faces thereof, as in Fig. 7 of the drawings, flexible label pickers 28, preferably constructed of rubber.

Mounted on suitable supports extending transversely between the uprights 1' near the upper ends thereof and arranged in pairs, one above the other, directly behind each pair of label picker chains 23 with their delivery end toward the label pickers carried by said chains, are neck and body label boxes 29 and 30, of a size adapted to contain respectively the neck and body labels which are removed therefrom, and carried into the path of the propelled bottles by the label pickers 28.

45 Mounted on suitable supports extending transversely between the uprights 1' and positioned at the front edges thereof so as to be engaged by the label pickers 28 in their path of movement from the table 9 toward the label boxes 29 and 30, are receptacles 31 adapted to contain an adhesive. The receptacles 31 are provided with transversely extending adhesive feed rollers 32, mounted within the receptacles 31 on a shaft 33, which 50 extends transversely through both receptacles 31 and its outer end is journaled in one of the vertical uprights 1', and provided with a grooved pulley wheel 34, around which extends a drive cord 35, the 55 other end of which extends around a grooved wheel 36 secured to one end of the shaft 21. The adhesive feed rollers contact with the peripheries of suitable adhesive applying rollers 37, which extend transversely of the 60 receptacles 31 and are journaled in the sides

of the frame thereof, the adhesive applying rolls 37 receive the adhesive from the rolls 32 and apply it to the exposed face of the label pickers 28.

The neck and body label boxes are provided with downwardly inclined delivery slots 38 and 39, positioned at the bottom thereof adjacent their forward ends, and through which the labels contained in said boxes are adapted to be projected one after the other in the following manner:—Extending transversely of the label boxes 29 and 30 and positioned above the delivery slots 38 and 39 therein are delivery rolls 40 and 41, mounted on and adapted to rotate with their respective shafts 42 and 43, which extend through the sides of the label boxes and are journaled in the uprights 1' of the frame, the shaft 42 being provided at one end with a suitable peripheral grooved wheel 44, around which extends a flexible connection 45, the other end of which extends around a suitable grooved wheel 46 on the corresponding end of the shaft 43. Secured to the end of the shaft 43 beyond the grooved wheel 46 is another grooved wheel 47, around which extends a flexible connection 48, the other end thereof extending around a suitable grooved wheel 49, loosely mounted on the opposite end of the drive shaft 2 from the gear wheel 17. The outwardly facing hub portion of the wheel 49 is inwardly beveled as at 50, and said bevel is adapted to be frictionally engaged by the cone surface 51 of a clutch member 52 keyed to rotate with the shaft 2, the clutch being operated in a hereinafter described manner.

The labels after being projected through the slots 38 and 39 in the label receptacles 105 are forced against the adhesively coated label pickers in the following manner:—Pivotedly mounted in the sides of the frame 1' and supported immediately below the rear walls of the slots 38 and 39 by the arms 53 110 are transversely extending rods 54, to which are attached, below each label box between the arms 53, a swinging plate 55, carrying on its lower edge an idler roller 56, and normally held out of engagement with the faces 115 of the label pickers by the coiled springs 57 attached thereto and to the underside of the label boxes. The rods 54 are each provided at one end with a downwardly projecting lug 58 which is adapted to be engaged respectively by the double rotary cam dogs 59 and 60 carried on the inner ends of shafts 61 and 62, journaled in the arms 1' below the rods 54. The shaft 61 is provided at its outer end with a toothed wheel 61' around 120 which extends an endless drive chain 62, the upper end of which is supported by and receives its power from a suitable gear 63 mounted on the shaft 21 adjacent the gear wheel 20. The shaft 62 receives its power 130

from an endless drive chain 64 which extends around a sprocket 65 on the shaft 61, and a sprocket 66 on the shaft 62, said construction being disclosed more fully in Figs. 3 and 6 of the drawings.

10 The label pickers will be supplied in their upward movement from the table 9, with a suitable adhesive and when in the downward movement, as in Fig. 7 of the drawings, they will be supplied with neck and body labels from the respective neck and body label boxes, and will place said labels in a position to be applied to the propelled bottle.

15 The no bottle no label feed device is constructed in the following manner:—Mounted on the top plate 9 of the frame 1, slightly in advance of the upright arms 1', are horizontally extending arms 67 and 68, pivoted midway of their length as at points 69 and 70 to the top plate 9 of the frame, the outer ends of the arms projecting slightly within the path of the propelled bottle in its movement toward the labeling mechanism, and 25 the end of the arm 67 being slightly in advance of the arm 68. The rear end of the arm 67 is provided with a suitable pin 71, which slides within a slot 72 in the forward end of a lever 73, pivoted as at 74 to a suitable support 75 on the frame 1, the lever being provided at its rear end with suitable curved arms 76 which engage in a groove 77 in the clutch member 52, keyed to the shaft 2, the face of the clutch being normally held from engagement with the grooved wheel 49 by the action of a coiled spring 78 attached to the arm 69, and to the top plate 9 of the frame. The arm 67 being actuated by a bottle in its movement toward 40 the labeling mechanism, will, through its coacting parts, force the clutch 52 which rotates with the shaft 2, into engagement with the grooved wheel 49 which, through the flexible connections hereinbefore mentioned 45 will operate the adhesive applying rolls and the rolls within the label boxes for projecting the labels therefrom. The arm 68, which is positioned to operate a short interval after the arm 67, is pivoted in its center to the top of the frame as at 70, and its rear end is provided with a pin 70' which operates through a slot 71' in the forward end of a lever 72' pivoted as at 73' to a bracket 74' carried by the frame in advance 55 of the shaft 2. The lever is formed at its rear end with oppositely curved arms 75' which extend into an annular groove 76' formed in the hub of the cone clutch 18 keyed to the shaft 2. The end of the arm 68 which is engaged by the bottle is provided with a rearwardly curved portion 77' which insures a prolonged contact with the bottle, as the actuation of this arm controls the operation of the endless chains carrying 60 the label pickers and the mechanism for po-

sitioning the labels onto the adhesively coated label pickers after the labels have been projected from the label boxes in a hereinbefore described manner.

70 The arrangement, timing and operation of the respective parts of the machine are such that as a bottle is conveyed toward the labeling mechanism and contacts with the outer end of the arm 67, the clutch 52 will be thrown into engagement with the wheel 49 rotating the wheel with the shaft 2, the wheel 49 through the flexible connections 48 and 45 rotating the shafts 43 and 42, which carry the delivery rolls 41 and 40, said delivery rolls contacting with the foremost label in their respective receptacles and projecting said label through the delivery slots 39 and 38. At the same time that the above cycle of operation is in progress and about completed, the bottle in its movement toward the labeling mechanism will contact with the arm 68 forcing the clutch 18 into engagement with the wheel 17, which will through the flexible connection 19 rotate the shaft 21 carrying the label picker chains in 80 the direction of the arrow—as in Figs. 1 and 7. As the label pickers 28 carried by the chains 23 in their movement from the table 9, pass the adhesive receptacles 31, the adhesive applying rolls 37 coat the same with a 90 film of adhesive and as the adhesively coated label pickers arrive in a position in front of the label boxes, the plates 55 which are pivoted below the delivery slots of the label boxes and onto which the labels are projected are forced against the label pickers by the double cam dogs 59 and 60, which are connected through the linked chains 62 and 64 with the shaft 21. The curved portion 95 77' of the arm 68 contacts with the bottle until the adhesively coated labels carried by the label pickers are in a proper position in the path of the propelled bottle, at which time the bottle passes the arm and the clutch is disconnected from the wheel 17 by the 105 tension of the spring. As the bottles to be labeled are conveyed between the pairs of label picker chains 23, they engage the label extending across the space formed therebetween, and as they continue to travel through the space formed between the label picker chains, the labels forced by the advancing bottle contact with flexible rubber wiper fingers 79, supported by uprights 80 and 80' attached to the top plate of the machine immediately in rear of the label picker chains 23. As the bottle continues in its path of travel, the label wipers 79 smooth out the label and press the adhesively coated edges thereof to the face of the bottle, as 115 disclosed in Figs. 8 and 9 of the drawings. The bottles after being labeled are moved by the bottle carriers onto endless conveying belts 81, which operate through grooves or 120 slots 82 in the rear end of the top 9 of the 130

frame, the forward ends of said belts extending around suitable pulleys 83 secured to the drive shaft 2, the rear ends of said belts extending around suitable pulleys or 5 idlers (not shown) located at any suitable point.

A swinging arm 84 is provided in the rear of each set of wipers for the neck and body label boxes, said arms carrying at their 10 outer ends suitable flexible positioning fingers 85, which fingers of the said arms on the same being swung inwardly bear on the central portion of the label between the wipers 79 and press the same against the 15 surface of the bottle for holding the label properly positioned thereon as subjected to the action of the wipers when passing therethrough. The operation and mounting of the sets of arms being the same, a description 20 of one set is thought will suffice.

The inner ends of the arms 84 are flattened and overlap each other forming a rule joint, and pivot about a stud 86 projecting upwardly from the upper surface of a block 25 87 slidably mounted on a shaft 88, secured at its forward end to the upright 80' and at its rear end to a vertically extending arm 89 extending from the top 9 of the frame. Each of the arms 84 is provided at the rear 30 edge of its flattened portion adjacent its pivot point with upwardly projecting lugs 90 and 91, which are adapted to contact respectively with suitable rearwardly extending flat arms 92 and 93, secured to the rear 35 face of the upright 80' at each side of the stud 86. As the block 87 is slid forward on the shaft 88 by the action of the flexible cord 87' extending from the lower face of the block and around pulleys 94 and 95 and 40 provided at its end with a suitable weight 96, the lugs 90 and 91 will be forced into contact with the ends of the flat arms 92 and 93 which will force the arms 84 into a horizontal aligned position—as in Figs. 4 and 45 10 of the drawings. The arms when in their aligned position will be engaged at their rear edges by a suitable spring actuated catch 97 and held in this position, with the fingers 85 pressing the label onto the bottle as the 50 bottle is advanced through the wipers. The bottles in their travel through the label wipers and onto the endless conveyer will slide the blocks 87 carrying the arms 84 rearwardly on the shafts 88, against the tension of the weights 96, until the downwardly 55 extending arms 98 on the catches 97 contact with the trips 99, and simultaneously therewith the upper surfaces of the arms are engaged by spring catches 100. The arms 60 are now free to pivot on their studs 86 and the action of the weights 96 will draw the blocks 87 forward and the arms 84 inwardly, away from the bottles, until they release themselves from under the catches 100 at 65 which time the lugs 90 and 91 will be en-

gaged by the flat arms 92 and 93, and the arms again forced to their aligned position, this operation being disclosed in Figs. 4, 5 and 10 of the drawings. The spring catch 100 and the trip 99 are adjustably mounted 70 on the respective upper and lower faces of a block 101 slidably mounted on the shaft 88.

The labels in the neck and body label boxes are advanced toward the delivery slot thereof by the slidable follower plate 102, in 75 the rear of the labels, which is adapted to be advanced toward the front of the box by the action of a weighted arm 103, carried by a suitable shaft 104, pivotally mounted in suitable uprights 105, extending from the sides 80 of the label boxes.

While it has been stated that neck and body label boxes may be carried by the machine, it is to be understood that one or more label boxes may be carried, so long as they 85 are positioned within the path of movement of the label pickers.

Having thus described the invention what we claim as new and desire to secure by Letters Patent is:—

1. In an apparatus for labeling cylindrical or other shaped containers, the combination with a label holding receptacle, label pickers, devices for applying an adhesive to said label pickers, means for removing a 95 label from said label receptacle and positioning the same on said adhesively coated label pickers, a reciprocating conveyer for the containers to be labeled, means for placing the label within the path of the propelled 100 container, and devices for wiping the label to the container.

2. In an apparatus for labeling cylindrical or other shaped containers, the combination with a label holding receptacle, label 105 pickers, devices for applying an adhesive to said label pickers, means for removing a label from said label receptacle and positioning the same on said adhesively coated label pickers, a reciprocating conveyer for the 110 containers to be labeled, means for placing the label within the path of the propelled container, devices for applying the label to the container, and means for holding the label to the surface of the container while 115 being applied thereto.

3. In an apparatus for labeling cylindrical or other shaped containers, the combination with a label holding receptacle, label pickers, devices for applying an adhesive to said label 120 pickers, means for removing a label from said label receptacle and positioning the same on said adhesively coated label pickers, a reciprocating conveyer for the containers to be labeled, means for placing the label 125 within the path of the propelled container, devices for wiping the label to the container, and means for holding the label to the surface of the container while being applied thereto.

4. In an apparatus for labeling cylindrical or other shaped containers, the combination with a label holding receptacle, label pickers, devices for applying an adhesive to said label pickers, said devices being thrown into operation by the bottle to be labeled, means for removing a label from said label receptacle and positioning the same on said adhesively coated label pickers, a reciprocating conveyer for the containers to be labeled, means for placing the label in the path of the propelled container, and devices for applying the label to the container.

5. In an apparatus for labeling cylindrical or other shaped containers, the combination with a label holding receptacle, label pickers, devices for applying an adhesive to said label pickers, means for removing a label from said label receptacle and positioning the same on said adhesively coated label pickers, said means being thrown into operation by the container to be labeled, a reciprocating conveyer for the containers to be labeled, and means for placing the label in the path of the propelled container.

6. In an apparatus for labeling cylindrical or other shaped containers, the combination with a label holding receptacle, label pickers, devices for applying an adhesive to said label pickers, said devices being thrown into operation by the container to be labeled, means for removing a label from said label receptacle and positioning the same on said adhesively coated label pickers, said means also being thrown into operation by the container to be labeled, a reciprocating conveyer for the containers to be labeled, means for placing the label in the path of the propelled containers, and devices for applying the label to the container.

7. In an apparatus for labeling cylindrical or other shaped containers, the combination with a label holding receptacle, label pickers, devices for applying an adhesive to said label pickers, means for removing a label from said label receptacle and positioning the same on said adhesively coated label pickers, a reciprocating conveyer for the containers to be labeled, endless chains for placing the label in the path of the propelled container, and devices for applying the label to the container.

8. In an apparatus for labeling cylindrical or other shaped containers, the combination with a label holding receptacle, label pickers, devices for applying an adhesive to said label pickers, means for removing a label from said label receptacle and positioning the same on said adhesively coated label pickers, a reciprocating conveyer for the containers to be labeled, endless chains for placing the label in the path of the propelled container, and devices for wiping the label to the container.

65 9. In an apparatus for labeling cylindri-

cal or other shaped containers, the combination with a label holding receptacle, label pickers, devices for applying an adhesive to said label pickers, means for removing a label from said label receptacle and positioning the same onto said adhesively coated label pickers, a reciprocating conveyer for the containers to be labeled, means for positioning the label in the path of the propelled container, devices for applying the label to the container, means for holding the label to the surface of the container while being applied thereto, and means for removing the container with its applied label from the apparatus.

10. In an apparatus for labeling cylindrical or other shaped containers, the combination with a label holding receptacle, label pickers, devices for applying an adhesive to said label pickers, means for removing a label from said label receptacle, means for positioning said label onto said adhesively coated label pickers, a reciprocating conveyer for the containers to be labeled, means for positioning the label within the path of the propelled container, devices for wiping the label to the propelled container, and means for holding the label to the surface of the container while it is being wiped thereon.

11. In an apparatus for labeling cylindrical or other shaped containers, the combination with a label holding receptacle, label pickers, devices for applying an adhesive to said label pickers, means for removing a label from said label receptacle and positioning the same onto said adhesively coated label pickers, a reciprocating conveyer for the containers to be labeled, means for positioning the label within the path of the propelled container, devices for wiping the label onto the propelled container, an arm for positioning the label onto the surface of the container while it is being wiped thereon, and means associated with said arm for removing the same from the applied label and returning said arm to a position to engage the next succeeding label as it is applied to the bottle.

12. In an apparatus for labeling cylindrical or other shaped containers, the combination with a label holding receptacle, label pickers, devices for applying an adhesive to said label pickers, means for removing a label from said label receptacle and positioning the same onto said adhesively coated label pickers, a reciprocating conveyer for the containers to be labeled, means for positioning the label within the path of the propelled container, devices for wiping the label onto the propelled container, an arm for positioning the label onto the surface of the propelled bottle as the same travels through the wiping devices, said arm adapted to travel with said bottle until the label is wiped thereon, and means

associated with said arm for removing the same from engagement with the applied label and returning said arm to a position to engage the next succeeding label as it is applied to the bottle.

13. In an apparatus for labeling cylindrical or other shaped containers, the combination with a conveyer for the container to be labeled, means for positioning a label in the path of the propelled container, including vertically extending spaced endless members, means for operating the members, and means for wiping the positioned label on the container as the latter is advanced by the conveyer.

14. In an apparatus for labeling cylindrical or other shaped containers, the combination with a conveyer for the container to be labeled, means for positioning a label in the path of the propelled container, including flexible spaced endless members, means for operating the members, means for holding a label against the container, and means for wiping the label onto the container as the latter is advanced by the conveyer.

15. In an apparatus for labeling cylindrical or other shaped containers, the combination with a conveyer for the container to be labeled, means for positioning a label in the path of the propelled container including vertically extending flexible spaced endless members, means for operating the endless members, means for delivering a label to said members, means for holding the

positioned label against the receptacle, and means for wiping the label on the bottle as it is advanced by the conveyer.

16. In an apparatus for labeling cylindrical or other shaped containers, the combination with a conveyer for the container to be labeled, means for positioning a label in the path of the propelled container, including vertically extending spaced endless members, means for operating the members, means for delivering a label to said members, controlled by the receptacle to be labeled on said conveyer, and means for wiping the label onto the receptacle as it is advanced by said conveyer.

17. In an apparatus for labeling cylindrical or other shaped containers, the combination with a conveyer for the container to be labeled, means for positioning a label in the path of the propelled container, including vertically extending parallel spaced flexible endless members provided with fingers, means for operating the members, means for applying paste to the fingers, means for delivering a label to the pasted surfaces of the fingers, and means for wiping the label onto the receptacle as it is advanced by said conveyer.

In testimony whereof I have signed my name to this specification in the presence of two subscribing witnesses.

GEORGE LEE BENDER.
